BOBBIN SUPPORTING DEVICE

Riley G. Lackey, New Holland, Ga., assignor to
 Draper Corporation, Hopedale, Mass., a cor-
 poration of Maine

Application November 23, 1934, Serial No. 754,513

5 Claims. (Cl. 139—251)

The present invention pertains to the replenishing mechanism of a bobbin changing loom and has more particular reference to the hopper portion thereof.

Bobbin changing looms are commonly provided with a hopper stand having an axial stud on which is rotatably mounted a carrier for reserve bobbins. The bobbin in position to be transferred is supported by a bobbin supporting device which may be pivotally mounted on a stud or pin in the lower edge of the hopper stand. Bobbin supports of the type herein involved are provided with spaced bearings extending on opposite sides of the hopper stand and engaging the bearing pin. Prior to the present invention the bearing pin mentioned was passed through and supported by an aperture in the lower edge of the hopper stand. This construction has been found to be unsatisfactory, partly because of the tendency of the pins to loosen in the hopper stand and partly because of the breakage of the cast iron hopper stands at the aperture due to the shock which accompanies transfer.

It is an object of the present invention to provide a supporting device for bobbin supports of the type mentioned, which supporting device shall be so constructed as to be always firmly held in place and which shall be supported from the axial stud of the hopper stand.

A further object is to provide a supporting device for the purpose mentioned which shall also serve as a patch device for repairing broken hopper stands.

To this end, the invention provides a supporting rod, preferably of wrought iron, supported at its upper end from the axial hopper stud and having its lower end bent to extend through the aperture in the hopper stand, the turned end of the rod having a bearing surface on each side of the stand to receive the spaced bearings of the bobbin support. I find that in most hopper stands which have been broken by shock applied to the bobbin support, only the material below the center line of the aperture is broken away. The supporting device of the present invention provides a new bearing pin for the bobbin support which is usable with broken hopper stands, provided only that the apertured portion of the latter be not entirely broken away.

The preferred embodiment of the invention is illustrated on the accompanying drawing, of which:

Fig. 1 is a view partly in section and partly in elevation showing the application of the device to a hopper stand;

Fig. 2 is a detail, to a larger scale, and Fig. 3 is a sectional view taken approximately on line 3—3 of Fig. 1.

In the loom shown on the drawing, a rotary hopper, including a hopper stand 1, is mounted on a breast beam 2 adjacent one end of the lay 3. A shuttle 4 is adapted to be picked along the lay in the usual manner, and to be received in a shuttle box 5. The filling supply in the shuttle is automatically replenished by bobbin changing mechanism including a transfer hammer 6 which drives a bobbin 7 from the hopper down into the shuttle. The supply of bobbins in the hopper is held by any suitable means (not shown) adapted to revolve on a stud 8 which is fixed in and extends axially of the hopper stand.

A bobbin support 9 bears against the bobbin next to be transferred and holds it up in proper position in the hopper. During the actual transfer the bobbin support yields, as shown on Fig. 2, to allow the bobbin to be moved downwardly by the transfer hammer.

The parts of the loom as thus far described are all old and well known in the art. They are of the present invention only in that they may be used in conjunction with other parts to form the complete operative combination hereinafter claimed.

I provide a novel form of supporting device for the bobbin support. This device, as shown on the drawing, may be comprised of a one piece rod 10, preferably forged from a piece of wrought iron. The upper end of the rod is flattened and formed into an eye 11 the axis of which is normal to the body of the rod. The eye is adapted to fit over the axial stud 8 being conveniently held between the hopper stand and the nut 12 by which the stud is conventionally secured in the hopper stand. Thus, the rod is supported from the strongest part of the hopper stand and is so supported without the addition of any new supporting devices.

The lower end of the rod 10 is bent into parallelism with the hopper stud 8, and passes through the aperture 13 usually formed in the hopper stand for receiving a bobbin supporting pin (not shown). The rod may be of any suitable cross section except that portions 14 and 15, on opposite sides of the hopper stand, must be smooth and cylindrical to constitute bearing portions for the spaced bearings 16, 17 of the bobbin support.

The bobbin support pivots on and is supported entirely by the turned end of the rod 10. The only other connection between the bobbin support and the hopper stand is a yielding connec-

tion 18 which is adapted to hold an arm 19 of the support in contact with stop lug 20 in the usual manner. Thus, the shock which is imparted to the bobbin support is transmitted to the hopper stand at the center thereof where it is strongest. This is of considerable importance in view of the fact that these hopper stands are made of cast iron, which breaks easily when subjected to shock.

10 It will be noted that the hopper stand shown on the drawing is unbroken in the region of the aperture 13. However, a great many hopper stands have been broken by the shock of transfer and for the most part only the material containing the lower half of the aperture 13 has broken away. While the breaking of even such a small piece prevents use of the hopper stand with prior supporting devices, my improved supporting rod can be used with such broken hopper stands as well as with new ones. Accordingly, the rod may be used as a patch device for repairing broken hopper stands.

Having fully disclosed the preferred embodiment of my invention, I claim:

- 25 1. A supporting device for the bobbin support of a bobbin changing loom, said device being comprised of a rod having an integral eye at its upper end which eye is adapted to engage the axial stud of a rotary hopper, the lower end of said rod being turned into parallelism with the axis of said eye and constituting a combined support and bearing for the bobbin support.
- 30 2. A supporting device for the bobbin support of a bobbin changing loom, said device being comprised of a one piece wrought iron rod having its upper end flattened and formed into an eye the axis of which is normal to the body of the rod, the lower end of said rod being turned into parallelism with the axis of said eye and said

turned end having bearing portions for the spaced bearings of a pivoting bobbin support.

3. A patch device for repairing a broken hopper stand of a bobbin changing loom, said device being comprised of a one piece wrought iron rod having its upper end flattened and formed into an eye the axis of which eye is normal to the body of the rod to permit the eye to engage over the axial stud of the hopper, the lower end of said stud being turned into parallelism with the axis of said eye and being adapted to engage in an aperture in the hopper stand, said turned end having bearing portions for receiving and supporting the spaced bearings of a bobbin support.

4. The combination of a hopper stand having an axial hopper stud therein, a supporting device comprised of a rod having an integral eye at its upper end engaging over said stud and having its lower end turned into parallelism with said stud, said turned end passing through an aperture in said hopper stand and being provided with bearing portions on opposite sides of said hopper stand and a bobbin support having spaced bearings by means of which it is journalled on and supported by the said bearing portions.

5. The combination of a hopper stand having an axial hopper stud therein, a supporting device comprised of a one piece wrought iron rod having its upper end flattened and formed into an eye which engages over said stud, said rod having its lower end turned into parallelism with said stud, said turned end passing through an aperture in said hopper stand and provided on opposite sides thereof with bearing surfaces, and a bobbin support pivotally mounted on said turned end by means of spaced bearings engaging said bearing surfaces.
